UNITED STATES PATENT OFFICE

2,421,509

LIFTER FOR HOT OR COLD CONTAINERS

William C. Knapp, Columbia, Pa.

Application January 12, 1945, Serial No. 572,497

1 Claim. (Cl. 294—31)

1

This invention relates generally to lifters or tongs for lifting jars, cans, preserving glasses and like containers in the processing of various foods in which extreme temperatures of heat and cold are required, injury to the processor's hands being avoided in the use of the lifters for the reason that the processor need not touch or grasp the containers directly in removing the same from the processor.

More specifically, the present invention contemplates improvements in lifting tongs suitable for the aforescribed purpose whereby the handling of the containers is facilitated and rendered more safe.

Among other objects of the invention is the provision of scissorlike handles for the tongs and a jaw structure of greater strength therefor whereby the containers may be gripped more firmly thereby, thus promoting increased safety to the processor and substantially obviating the possibility of the containers slipping out of contact with the jaws.

Still other objects and advantages of the invention are those implied from or inherent in the novel construction of the lifting tongs as will become more clearly apparent as the description proceeds, reference being had to the accompanying drawings in which:

Figure 1 is a view in elevation of a lifting tongs constructed in accordance with one form of the invention and shown clamped to a container in a manner to lift the same,

Figure 2 is a side elevation of the lifting tongs shown in Figure 1,

Figure 3 is a sectional view taken along the line 3—3 of Figure 1,

Figure 4 is a perspective view of the lifting tongs shown in Figure 1,

Figure 5 is a view in elevation of a lifting tongs constructed in accordance with a second form of the invention and illustrates the manner of clamping the same to a container,

Figure 6 is a sectional view as seen along the line 6—6 of Figure 5,

Figure 7 is a side elevation of the lifting tongs shown in Figure 5,

Figure 8 is a perspective view of a portion of the lifting tongs shown in Figure 5, and

Figure 9 is a perspective view of a portion of a lifting tongs constructed in accordance with a third form of the invention.

Referring now to the drawings and more particularly to Figures 1 through 4 thereof, the numeral 10 generally designates a lifting tongs according to one form of the invention. Tongs 10

2

comprises a pair of identical levers disposed in crossed relation in the manner of the well-known ice tongs and pivotally joined as at 11 by a suitable transverse pin, rivet, screw or the like. Each of the levers comprises a flattened surface 12 of sufficient area within the vicinity of pivot 11 to insure a firm joint between the levers and at the same time to provide sufficient freedom of movement therebetween as the tongs is operated.

The flat portions 12 of the levers define a figure X when the tongs are assembled, the top portion of the X terminating preferably in rounded upwardly extending and substantially parallel handle portions 13 of sufficient length to provide adequate leverage and to insure that the processor's hands are at a safe distance from the processor when the grip portions 14 of the tongs are grasped. Each of the handle grips 14 is preferably formed in a loop which lies substantially within the plane of the flattened portion 12 formed integrally therewith, thus providing a scissor-like handle grip adapted to accommodate one or more fingers of the hand, as is desired. The nicety of such handle grips in applying pressure to the tongs is readily apparent.

The lower portions of the X defined by flat portions 12 terminate preferably in rounded downwardly extending and substantially parallel jaw portions 15 which are spaced sufficiently apart to clear substantially all processing containers of standard sizes, a Mason jar 16 being shown to illustrate the proportions of a satisfactory tongs.

Each of jaws 15 has laterally extended therefrom and secured thereto or integrally formed therewith a preferably rounded and arcuate member 17 adapted snugly to engage the jar 16 below the rubber washer seat 18 thereof when pressure is applied to the tongs.

Referring now to Figures 5 through 8, the numeral 20 generally designates another lifting tongs constructed according to an alternate form of the invention, tongs 20 being generally similar to tongs 10 except that the jaws 21 of tongs 20 are bifurcated and both bifurcated ends are secured to or formed integrally with the arcuate members 17 intermediate the ends thereof, thereby to provide an inherently stronger jaw structure adapted to distribute the pressure applied to the arcuate members more evenly over the length thereof, and to grip the container more firmly.

Tongs 22 disclosed in Figure 9 are generally similar to tongs 20 except that the bifurcated jaws 23 of tongs 22 are secured to the ends of

arcuate members 17 or formed integrally therewith, as the case may be.

While but three embodiments of the invention have been disclosed which give satisfactory results, it will be apparent to those skilled in the art that additional forms of the invention may be provided without departing from the spirit and scope of the invention as defined by the appended claim.

I claim as my invention:

Lifting tongs comprising a pair of arcuate jaws, each having backwardly parallel portions, said backwardly parallel portions being provided with upstanding parallel portions, said upstanding parallel portions having inclined converging and meeting portions, a pair of handles having crossed and pivotally connected portions, each of the said

crossed portions merging with a corresponding meeting point of the converged and inclined portions.

WILLIAM C. KNAPP.
